Term of patent 14 years

(Cl. D1—12)

FIG. 1.

FIG. 4.

FIG. 3.

FIG. 2.

FIG. 1 is a front perspective view of an illuminable sign showing my new design, the center panel being in a rotated position;

FIG. 2 is a front elevational view thereof, the center panel being rotated into the plane of the sign;

FIG. 3 is a rear elevational view thereof, the center panel being in the same position as in FIG. 2; and

FIG. 4 is a side elevational view thereof, the center panel being in the same position as in FIG. 2.

The dominant features of my design reside in the full line portions of the drawing.

I claim:

The ornamental design for an illuminable sign substantially as shown and described.
